UNITED STATES PATENT OFFICE.

DRACOS SOUTER, OF BATON ROUGE, LOUISIANA.

HOSE-HOLDER.

1,372,571.

Specification of Letters Patent. Patented Mar. 22, 1921.

Application filed November 17, 1920. Serial No. 424,736.

To all whom it may concern:

Be it known that I, DRACOS SOUTER, a citizen of the United States, residing at Baton Rouge, in the parish of East Baton Rouge and State of Louisiana, have invented 5 certain new and useful Improvements in Hose-Holders; and I do hereby declare the following to be a full, clear, and exact description of the invention, such as will enable others skilled in the art to which it appertains to make and use the same.

The present invention relates to improvements in hose holders, and has for an object to provide an improved device of this character more particularly for use in supporting fire hose and the like on fire tug boats and also on vessels generally, where it is required that the hose be supported out of the way, but at the same time be easily accessible and removable in case of emergency.

It is another object of the invention to provide an improved hose holder which will be substantially automatic in action in allowing of the removal and replacement of the hose and which will effectively retain the hose until it is grasped and positively pulled therefrom.

A further object of the invention resides in providing an improved hose holder of simple and inexpensive construction; which involves the production of a novel form of bracket attachable to either right or left walls or to ceilings at will; and which further involves the provision of a swinging frame adapted to guide a pair of weighted arms to which the pivoted jaws which clamp the hose therebetween are secured, and which thereby insures the positive opening and closing of the jaws.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a front view of an improved hose holder constructed according to the present invention and illustrating a fragmentary piece of hose as held therein;

Fig. 2 is a side view thereof; and

Fig. 3 is a fragmentary plan view.

Referring more particularly to the drawings, the improved supporting bracket is

composed of a single piece of heavy gage wire or metallic rod construction so shaped and designed as to provide a pair of parallel members each composed of angularly disposed arms 1 and 2 which may be slightly curved as indicated in Fig. 2. The arms at their convergent meeting ends are coiled into one or more convolutions 3 adapted to receive the pivot pin 4. The free ends of the arms of adjacent members are connected together by rods 5 and 6, eyes 7 and 8 being made at the ends of such members 5 and 6 in order to receive screws or other fastenings 9 and 10 which take into a wall or other support, as indicated in Fig. 2.

A rectangular open swinging frame 11 is also made of a single piece of heavy gage wire of round bar construction bent to provide parallel sides and ends and formed with upstanding eyes or convolutions 12 and 13 adapted to come into alignment with the convolutions 3 in order to receive the pin 4 on which the frame 11 may freely rock. The pin 4 extends above the intermediate portion of the frame 11 leaving spaces to either side of the pin in which to slidably receive and guide pairs of parallel arms 14 and 15 which connect with the hose clamping jaws 16 and 17. The parallel arms 14 and 15 are connected together by rods 18 and 19 which carry weights 20 and 21 of such mass that they will sustain the jaws and the weight of the hose carried thereby in the upper full line position indicated in Fig. 2. The hose is represented at 22 in Fig. 1 and is illustrated as being clamped tightly by the jaws 16 and 17, which jaws are in the upper position. The lower ends of the jaws preferably overlap beneath the hose as indicated in full lines in Fig. 2 in order to more effectively support the hose and avoid the accidental opening of the jaws by its weight.

When the jaws 16 and 17 open, the overlapped ends thereof swing widely apart, thus affording an ample gap from which the hose may fall and into which it may be pushed upwardly when replacing it. The jaws 16 and 17 are likewise composed of parallel and spaced apart members connected at their lower ends by bars 23 and 24 and each member of each jaw is curved semi-circularly so as to fit substantially about one-half of the hose 22. At the upper ends of the jaws convolutions 25 and 26 are made in registry

to receive the pivot pin 27 by which the two jaws are swingingly associated. The jaw 16 is formed in one piece with the arm 14 and the jaw 17 in one piece with the other arm 5 15, the arms 14 and 15 rising from the convolutions 25 and 26.

In use, the hose 22 is normally supported as shown in Fig. 1 and in full lines in Fig. 2. The arms 14 and 15 are in their divergent position so that the weights 20 and 21 exert a comparatively great leverage to hold the jaws closed and the hose elevated. When emergency arises the hose 22 may be grasped and pulled downwardly. This will 10 cause the jaws 16 and 17 to descend from the full to the dotted line position shown in Fig. 2. This descent causes the arms 14 and 15 to be drawn through the rectangular frame 11. The arms are thereby swung 15 toward one another guided between the sides of the frame 11 and the pin 4, and they are thus brought to the dotted line position causing the opening of the jaws 16 and 17 and the release of the hose. This brings the 20 open jaws 16 and 17 at a lower elevation so that in replacing the hose the jaws are more easily accessible.

In the act of replacing the hose the same is moved upwardly until it strikes the pivot 30 point of the jaws whereupon the jaws and the arms are carried upwardly therewith. The pin 4 will cause the curved arms 14 and 15 to diverge and close the jaws 16 and 17 about the hose. When the hose is moved upwardly to the full extent the weights 20 and 21 will then occupy a position to support the hose and to maintain the jaws 16 and 17 closed.

It will be understood that the supporting 40 bracket may be swung on the pivot 4 to any position, for instance, so that the fastenings 9 and 10 may be engaged with the opposite wall or with the ceiling.

It is obvious that various changes and 45 modifications may be made in the details of construction and design of the above specifically described embodiment of this invention without departing from the spirit thereof, such changes and modifications being restricted only by the scope of the following claims.

What is claimed is:

1. A hose holder comprising supporting means, openable jaws adapted to clamp the hose therebetween held by said supporting means, and weight-imposing means integral with the jaws and acting thereon to normally and yieldably hold said jaws upon the hose, substantially as described.
2. An improved hose holder comprising supporting means, pivoted jaws adapted to clamp the hose therebetween and having arms extending above the pivot point of the jaws and being slidably engaged with said 60 supporting means, said arms being weighted

to hold the jaws in the closed position, substantially as described.

3. An improved hose holder comprising a supporting bracket, a frame held by said bracket, a pair of pivoted jaws, and weighted 70 arms extending from said jaws and slidably received in said frame, substantially as described.

4. An improved hose holder comprising a supporting bracket, a rectangular open 75 frame swinging on the supporting bracket, a pair of pivoted jaws adapted to clamp the hose therebetween and being movable as a unit with respect to said bracket and swinging frame, and a pair of weighted arms connected to said jaws and being slidably movable through the rectangular frame, substantially as described.

5. An improved hose holder comprising a supporting bracket, a swinging rectangular 85 open frame carried by said bracket, a pair of jaws pivoted together and adapted to clamp a hose therebetween, arms integral with said jaws and extending in a direction oppositely to the jaws and in divergent relation, said arms being slidably mounted through said rectangular open frame and adapted to be guided thereby, and weights carried by the outer divergent ends of said arms, substantially as described.

6. An improved hose holder comprising a bracket composed of a pair of parallel members, each of said members composed of a pair of arms angularly disposed and provided with convolutions at their intermediate convergent portions, fastening means adapted to engage with the free ends of said arms whereby to attach the bracket to a support, a rectangular open frame having upstanding convolutions at its ends adapted to 105 align with the convolutions of the bracket, a pin passing through the several convolutions to swingingly support the frame from the bracket, a pair of jaws pivoted together and adapted to clamp the hose therebetween, and weighted arms integral with the jaws and extending upwardly and outwardly from the pivot point thereof, said weighted arms being slidably received in the rectangular frame and being guided thereby and by said 110 pivot, substantially as described.

7. An improved hose holder comprising a bracket adapted to be attached to a support, a pivot carried by said bracket, an open rectangular frame swinging on said pivot, a 115 pair of jaws pivoted together and adapted to receive a hose therebetween, and arms connected to said jaws and extending through the rectangular open frame and being guided by the sides of the frame and by 120 said pivot, each of said jaws and its companion arm being formed in one piece, substantially as described.
